UNITED STATES PATENT OFFICE.

GEORGE A. GILBERT, OF BREWSTER, AND GRACE H. STEPHENS, OF PATTERSON, NEW YORK, ASSIGNEES OF ONE-THIRD TO DANIEL M. STEPHENS, OF PATTERSON, NEW YORK.

CAR-STEP.

1,341,310.

Specification of Letters Patent.

Patented May 25, 1920.

Application filed September 19, 1919. Serial No. 324,896.

To all whom it may concern:

Be it known that we, GEORGE A. GILBERT and GRACE H. STEPHENS, citizens of the United States, residing at Brewster and Patterson, respectively, both in the county of Putnam and State of New York, have invented certain new and useful Improvements in Car-Steps, of which the following is a specification.

10 This invention relates to car steps, and more particularly to a car step of the extension type.

One of the main objects of the invention is to provide a supplemental step for cars 15 which may be readily applied to the frame of the step of common construction now used in which the bottom step of the flight is usually spaced a considerable distance above the ground surface, this supplemental 20 step being capable of being lowered to within a short distance of the ground surface. A further object is to provide a supplemental step of the character stated and simple and efficient means for raising and lowering the 25 same and securing it in adjusted position. Another object is to provide a supplemental step and supporting means therefor which may be produced at relatively small cost, this supporting means being so constructed 30 as to be readily applied to the side frame of the rigid car step without necessitating any appreciable alteration in the construction of the same. Further objects will appear from the detailed description.

35 In the drawings:

Figure 1 is a side view of a supplemental step showing an adjusting means therefor constructed in accordance with my invention as applied to a usual type of car step,

40 Fig. 2 is a front view of the same.

The car steps A are of standard construction, the step boards or flights 1 being supported between the downwardly and outwardly inclined side boards 2. The steps 45 or stairs constructed in this manner are of well-known construction and project downwardly and outwardly from the platform of the car. A supporting frame 3 is slidably mounted on each side board 2, on the outer 50 surface thereof. This frame 3 is provided with side bars 4 and 5, lower end bar 6, and upper end bar 7. The upper end bar is provided, at each end, with an outwardly and downwardly curved ear 8. These ears are 55 curved so as to fit snugly about the upper portion of bearing rollers 9 which are rotatably mounted on the end portions of cross rods 10 secured through the side boards 2 of the frame. These rollers 9 are positioned in horizontal alinement, and are so spaced as to snugly receive between them the side bars 4 and 5 of frame 3. The rollers thus act as guide members and also as stops for positively limiting downward movement 60 of frame 3. The outer rod 10 has one end extended to provide a bearing member 10^a which projects beyond the outer face of the forward roller 9. A hand lever 11 is rockably mounted on this bearing member and is provided adjacent its lower end with a 65 longitudinal slot 12 which receives a stud 13 projecting outwardly from a lug 14 formed on the inner face of side bar 5. Hand lever 11 carries a slidable rod 15 which is actuated by a hand latch 16 and is provided at its 70 lower end with a head 17 adapted to engage into a coöperating recess formed in the upper face of a plate 19 secured to the outer face of side board 2 adjacent the inner edge thereof. Plate 19 is so positioned that, when 75 head 17 is in engagement with the recess formed therein, the slidable frame 3 will be held in raised position by lever 11 as shown in Fig. 1.

A supplemental step 20 is secured between 80 the lower ends of the frames 3 and is of such length as to extend the full width of the stair frame which supports rigidly the stair flights 1. When in raised position, this supplemental step fits snugly beneath the 85 lowermost flight 1 of the rigid step. By releasing hand levers 11 from plate 19, the frame 3 will slide downwardly by gravity so as to bring the step 20 in position below the lowermost flight 1 and to within a short 90 distance of the ground surface, thus facilitating entry of persons into the car. This downward movement of the supplemental step is positively limited by engagement of the arcuate ears 8 with the rollers 9. The 95 rollers thus serve to support the supplemental step in lowered position, as indicated in Fig. 1. Also, as the ears 8 are curved downwardly and engage about the upper portions of the rollers, the rollers coöperate 100 with the ears to prevent looseness or play forwardly or rearwardly of the frame 3. To securely brace the frame 3 against rearward movement, we provide rollers 21 adjacent the lower end of each side board 2. These 105 110

rollers are mounted on a cross rod 22 secured through the side boards and positioned intermediate the two lower steps or flights 1 and are so related to the lower side bars 5 of the 5 frames as to form supporting members therefor. The rollers 9 and 21 coöperate to provide anti-friction bearings for the slide-able frame, and also serve to secure the frame against rearward movement in the manner 10 described. When it is desired to return the supplemental step to raised or inoperative position, this is readily accomplished by swinging the hand lever 11 downwardly and outwardly so as to bring the lower end 15 thereof above plate 19, after which the detent 17 is moved into engagement with the recess in this plate, thus releasably locking the slideable frame 3 for the supplemental step, composed of the side bars 4 and 5 in raised 20 position.

It will be evident that means other than illustrated may be used for raising and lowering the supplemental step, but for ordinary purposes we prefer to use the hand 25 lever shown. It will also be evident that there may be slight changes made in the construction and arrangement of the different

parts of our invention without departing from the field and scope of the same, and we intend to include all such variations, as fall 30 within the scope of the appended claim, in this application in which a preferred form only of our invention is disclosed.

What we claim is:

In car steps, a rigid step frame extending 35 at an angle, a pair of horizontally alined rollers mounted on said frame, a single roller mounted beneath the outermost of said pair of rollers, a second frame, bearing against the innermost of the first mentioned pair of 40 rollers and the bottom roller, a horizontal member on the upper end of said second frame terminating in semi-circular ears designed to rest upon the pair of rollers when the frame is in the lower most position, 45 and a car step carried by the lower end of said second frame.

In testimony whereof we affix our signatures in presence of two witnesses.

GEORGE A. GILBERT. [L.S.]
GRACE H. STEPHENS. [L.S.]
